UNITED STATES PATENT OFFICE.

ESTELLE VALRIE ALLISON, OF NEW YORK, N. Y.

DESIGN FOR A DRESSED DOLL.

58,297.

Specification for Design.

Patented July 12, 1921.

Application filed January 26, 1920. Serial No. 354,257. Term of patent 7 years.

To all whom it may concern:

Be it known that I, ESTELLE VALRIE ALLISON, a citizen of the United States, residing at the city, county, and State of New York, have invented a new and original and ornamental Design for Dressed Dolls, of which the following is a specification, reference being had to the accompanying drawing, forming part thereof.

The figure is an elevation of the doll showing my new design.

I claim—

The ornamental design for a dressed doll as shown.

ESTELLE VALRIE ALLISON.
